(57) **CLAIM**

The ornamental design for an eye anti-wrinkle device, as shown and described.

DESCRIPTION

1. Eye anti-wrinkle device

1.1 is a perspective view showing the eye anti-wrinkle device of my design;

1.2 is a front elevational view thereof;

1.3 is a rear elevational view thereof;

1.4 is a left side elevational view thereof;

1.5 is a right side elevational view thereof;

1.6 is a top plan view thereof; and

1.7 is a bottom plan view thereof.

The portions of the eye anti-wrinkle device shown in broken lines are included for the purpose of illustrating unclaimed portions of the eye anti-wrinkle device and form no part of the claimed design.
